ATTORNEYS.

UNITED STATES PATENT OFFICE.

CHRISTOPHER C. SHARP, OF INDIANAPOLIS, INDIANA.

PESSARY.

SPECIFICATION forming part of Letters Patent No. 395,008, dated December 25, 1888.

Application filed July 20, 1888. Serial No. 280,489. (No model.)

To all whom it may concern:

Be it known that I, CHRISTOPHER C. SHARP, a citizen of the United States, residing at Indianapolis, in the county of Marion and 5 State of Indiana, have invented certain new and useful Improvements in Uterine Supporters, of which the following is a specification.

My said invention consists in an improved 10 construction of uterine supporters, whereby a very convenient and perfect instrument of this character is provided, which can be worn with ease and comfort and one which will be retained in position by the walls of the vagina 15 without the assistance of any exterior means, as will be hereinafter more fully described and claimed.

Referring to the accompanying drawings, which are made a part hereof, and on which 20 similar letters of reference indicate similar parts, Figure 1 is a sectional view of a portion of the female body illustrating the use to which my invention is applied, the organs being shown in their natural position and the 25 uterus as supported by the assistance of my invention; Fig. 2, a perspective view of the supporter separately, on an enlarged scale; Fig. 4, a sectional view through the same, and Fig. 3 a view of a slightly modified construc- 30

The supporter consists of the cup-shaped portion A, constructed preferably of hard rubber or a similar material, and formed to receive the lower end of the uterus or womb in 35 a similar manner to that in which a similar part of other supporters receive the same organ. It is formed with a central perforation, in which is mounted a screw-threaded stud, a, which is formed with a large flat head adapted 40 to fit closely in the bottom of said cup-shaped part, the stud projecting downwardly through the same. A part, A', formed to fit closely against the under side of said part A, is mounted on the lower end of said stud by 45 means of a central screw-threaded perforation, a'. It is also formed with a downwardly-projecting stem provided with a transverse perforation, a², in which a cord, a³, is secured. Interposed between the part A and the part A', 50 and secured in position by being tightly clamped between them, is a ring, A², of elastic

material—such as gutta-percha or rubber—which is formed of a width to extend out from the base of said cup-shaped part a sufficient distance to fill the cavity which naturally exists in the vagina just below the lower end of the uterus. 55

Perforations a⁴ are provided in the supporter, which extend from the bottom of the cup-shaped part A down through the several 60 parts, to permit the discharge of any secretions or products of the uterus that may collect therein.

The use of my invention is as follows: When the uterus is in its natural position, the walls 65 of the vagina close nearly together a short distance below its lower end, thus leaving a cavity around this part of the organ, which is to a certain degree a vacuum, and said walls being closed together at this point an inclined 70 surface is provided possessed of considerable strength or resistance. It being necessary to employ the services of an instrument of this character to assist the natural organs to support the uterus or womb from any cause, the 75 organ is adjusted to its normal position and the supporter is inserted in the vagina to that position, where the lower end of said organ will rest in the cup-shaped part A, when the soft elastic annular flange or ring A² will 80 spread out and rest against the walls of the vagina, which contract behind it, as before described, and thus sustain the instrument in this position without the assistance of any other artificial means. When it is desired to 85 remove it, it can be done by means of the cord a³, which is usually of silk or other soft material, and extends out where it can be conveniently reached. By this means a supporter is provided which has no hard or rigid parts 90 to irritate the vagina or other organs and render the use of the instrument injurious, uncomfortable, or disagreeable; but, on the contrary, it adds greatly to the comfort and ease of those who need its services. 95

In Fig. 3, I show the same construction, except that in lieu of the ring A², I substitute a bunch of cotton or similar material, which is placed over the top of the cup and preferably hangs down in quite a quantity beneath said 100 cup. This form is designed for use in case of a diseased uterus, when it is necessary to ap-

ply medicine thereto, the medicine being placed upon the cotton in the cup-shaped part and thus applied directly to the diseased organ in a very efficient manner. It is placed 5 in position in the same manner as the other construction, except that the cotton is wadded up behind the cup-shaped part to fill the cavity before described and sustain the instrument in position. Occasionally it is necessary to 10 support the organ in one direction or the other from the surrounding organs, and in such cases the cotton can be placed on that side where it will support the organ in the position desired, as will be readily understood.

15 Having thus fully described my said invention, what I claim as new, and desire to secure by Letters Patent, is—

1. The combination, with a uterine supporter, of an annular flange or ring secured to 20 and extending out from the base thereof to rest against the walls of the vagina, substantially as described, and for the purposes specified.

2. In a uterine supporter, the combination of the cup-shaped part A and the elastic ring 25 A², secured to the base of said part A and extending out therefrom, substantially as described, and for the purposes specified.

3. The combination, in a uterine supporter, of the cup-shaped part A, the screw-threaded 30 stud a, extending down from its bottom, the part A', screwed onto said stud, the annular ring A², extending out from the base of said cup-shaped part, as described, and perforations formed through the bottom of the device, substantially as set forth.

In witness whereof I have hereunto set my hand and seal at Indianapolis, Indiana, this 17th day of July, A. D. 1888.

CHRISTOPHER C. SHARP. [L. s.]
